UNITED STATES PATENT OFFICE.

MURRAY W. FERRIS, OF SOUTH ORANGE, NEW JERSEY.

SHOULDER-BRACE.

No. 903,073.

Specification of Letters Patent.

Patented Nov. 3, 1908.

Application filed June 8, 1908. Serial No. 437,811.

To all whom it may concern:

Be it known that I, MURRAY W. FERRIS, a citizen of the United States, and a resident of South Orange, in the county of Essex and State of New Jersey, have invented new and useful Improvements in Shoulder-Braces, of which the following is a full, clear, and exact description.

The invention relates to wearing apparel, and its object is to provide certain new and useful improvements in shoulder braces, tending to hold the body of the wearer in proper position, with a view to insure an upright, healthy carriage, at the same time allowing sufficient yielding for the comfort of the wearer, protecting the arm straps against perspiration, preventing the shoulder straps from accidentally sliding off the shoulders, and allowing convenient adjustment to accurately fit the wearer's body.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in all the views.

Figure 1 is a front perspective view of the improvement as applied; Fig. 2 is a rear perspective view of the same; Fig. 3 is an enlarged sectional plan view of the pocket and elastic band of one of the shoulder straps, the section being on the line 3—3 of Fig. 2; Fig. 4 is an enlarged cross section of the same on the line 4—4 of Fig. 2; and Fig. 5 is an enlarged transverse section of one of the shoulder straps.

As shown in Figs. 1 and 2, the shoulder brace in its general construction embraces a girdle A, crossing back straps B, B', shoulder straps C, C' and elastic bands D, D' secured on the terminals of the shoulder straps C, C' and extending into pockets E, E' formed on the back straps B, B', the lower end of the said elastic bands D, D' being secured by stitches or other fastening means F to the pockets E, E' at the lower portions thereof, as plainly indicated in Fig. 3. The girdle A is made in two parts A', A² fastened together by a lacing G, and the lower end of the back strap B is removably connected by buttons H or other fastening means to the rear end of the girdle part A'. The other back strap B' is integrally connected at its lower end with

the rear end of the other girdle part A², and by adjusting the lacing G the parts can be conveniently adjusted to fit the wearer's body, it being understood that for attaching 60 the shoulder brace or removing the same it is only necessary for the wearer to fasten or unfasten the back strap B at the fastening devices H.

Each of the shoulder straps C, C' has its 65 top portion formed of a transversely shirred band C² connected to narrow strips C³, so that the shirred bands C² snugly fit onto the top of the wearer's shoulders, and at the same time the shirred or plaited parts securely 70 hold the shoulder straps from slipping off the wearer's shoulders. The portions of the shoulder straps C and C' passing under the arms of the wearer are in the form of pockets C⁴ containing a suitable filling C⁵, to render 75 the said portions padded and easy under the arms, without danger of chafing the same. The inner sides of the pockets C⁴ are formed of a waterproof material, so as to render the pockets impervious to perspiration, thus protecting the padded pockets against injury by 80 perspiration.

By having the elastic bands D, D' arranged as described, the shoulder straps C, C' can yield sufficiently to allow the desired comfort to the wearer when moving the arms or body.

The portions of the back straps B, B' adjacent to the pockets E, E' are preferably stiffened by whalebones or other stiffeners B² 90 (see Figs. 2 and 4.)

It is understood that after the girdle parts A', A² are adjusted by the lacing G, no further adjustment is required, and its adjustment is not disturbed as it is only necessary 95 for the wearer to button and unbutton the back strap B at the girdle part A' after placing the brace in position on the body or previous to removing the same therefrom.

Having thus described my invention, I 100 claim as new and desire to secure by Letters Patent:

1. A shoulder brace provided with shoulder straps having shirred top portions for engagement with the top of the shoulders to 105 hold the straps against slipping.

2. A shoulder brace provided with shoulder straps widened at the top and each having inelastic narrow side strips, and a shirred band connecting the said side strips with 110 each other.

3. A shoulder brace provided with shoul-

der straps having shirred top portions for engagement with the top of the shoulders, the portion of each strap extending under the arm of the wearer being in the form of a 5 pocket, and a padding filling the same.

4. A shoulder brace provided with shoulder straps having top portions for engagement with the top of the shoulder, the shoulder straps each having elastic terminals, the portion 10 of each strap between the top portion and the elastic terminal being in the form of a pocket, and a padding filling the same, the pocket portion of each shoulder strap being arranged to extend under the arm of the 15 wearer, and the under side of each pocket being of waterproof material.

5. A shoulder brace provided with back straps and shoulder straps connected with the upper ends of the back straps and having 20 top portions for engaging the shoulders, the shoulder straps being adapted to pass under the arms of the wearer and having elastic terminals at their forward ends secured to the back straps, the portion of each shoulder 25 strap extending under the arm being in the form of a pocket, and a padding filling the same, the under side of each pocket being of a waterproof material.

6. A shoulder brace provided with back 30 straps, each having a pocket, and shoulder straps forming a continuation of the back straps at one side of the pockets, and elastic bands secured to the terminals of the shoulder straps and extending into the said pock- 35 ets and secured therein at the ends.

7. A shoulder brace provided with back straps, each having a pocket and shoulder straps forming a continuation of the back straps at one side of the pockets, and elastic 40 bands secured to the terminals of the shoulder straps and extending into the said pock- ets and secured therein at the ends, the inner sides of the pockets being of waterproof material.

45 8. A shoulder brace, comprising a girdle, back straps connected at their lower ends with the ends of the said girdle, shoulder

straps forming integral continuations of the upper ends of the said back straps, elastic bands fixed on the terminals of the shoulder 50 straps, and pockets on the said back straps and into which extend the said elastic bands, the ends of which are fastened in the pockets.

9. A shoulder brace, comprising a girdle made in parts and a lacing for connecting the 55 said parts with each other, a back strap integrally connected at its lower end with the rear end of one of the said girdle parts, and provided at the upper portion with a pocket, a second back strap provided at its upper portion with a pocket, fastening devices for removably fastening the lower end of the said second back strap to the rear end of the other girdle part, shoulder straps extending integrally from the upper ends of the said back 60 straps, and elastic bands on the forward ends of the shoulder straps and extending into and secured to the said pockets.

10. A shoulder brace, comprising a girdle made in parts and a lacing for connecting the 70 said parts with each other, a back strap integrally connected at its lower end with the rear end of one of the said girdle parts, and provided at the upper portion with a pocket, a second back strap provided at its upper 75 portion with a pocket, fastening devices for removably fastening the lower end of the said second back strap to the rear end of the other girdle part, shoulder straps extending integrally from the upper ends of the said back 80 straps, and elastic bands on the forward ends of the shoulder straps and extending into and secured to the said pockets, the shoulder straps having shirred top portions to hold the shoulder straps against slipping on the 85 wearer's shoulders.

In testimony whereof I have signed my name to this specification in the presence of two subscribing witnesses.

MURRAY W. FERRIS.
